ARRANGEMENT FOR CONDUCTING HEAT AND HIGH-FREQUENCY CURRENTS

Harold A. Wheeler, Great Neck, N. Y., assignor,
by mesne assignments, to Hazeltine Research,
Inc., Chicago, Ill., a corporation of Illinois

Application February 21, 1946, Serial No. 649,846

6 Claims. (Cl. 178—44)

1

This invention relates to improved conductive arrangements adapted to be employed in the generation and transmission of high frequency currents and, more particularly, to an arrangement for efficiently dissipating heat from a conductor while at the same time providing a low impedance path for high frequency currents. As used throughout the specification and in the appended claims, the term "high frequency" refers to radio frequencies so high that the current path therefor is predominantly determined by the well-known "skin effect." While the invention may be applied to any high frequency current distribution system, it is especially suited for use with electron-discharge devices and will be particularly described in that connection.

One type of heat-conductive arrangement which has previously been used for cooling the anode of a vacuum-tube oscillator consists of a plurality of radiator elements, transversely mounted on an extension of the anode lead and cooled by water or an air blast. In such a case it is necessary to connect the anode to ground in such a manner as to complete the high frequency circuit without the passage of current through the radiator assembly. Another type of heat-conductive arrangement which has been used consists of a plurality of cooling elements mounted in longitudinal relation to an anode conductor. Such a cooling arrangement is inefficient when used with a transversely directed air blast and it can only be used in an open space where air may be directed along the cooling fins.

It is an object of this invention, therefore, to provide an arrangement for conveying heat and high frequency currents which avoids one or more of the disadvantages of prior arrangements.

It is a further object of the invention to provide an improved arrangement for conveying heat and high frequency currents including one set of elements for efficient heat dissipation and another set of elements for efficient current transmission.

In accordance with the invention, an arrangement adapted to convey heat and high frequency currents from a source comprises a conductor of heat and high frequency currents and a thermal radiator which includes a plurality of heat-conductive elements of relatively large areas secured in transverse relation to, and spaced along, the longitudinal axis of the conductor to provide a large heat-dissipating area but presenting a high impedance to the flow of high frequency currents along the radiator. The arrangement also includes a plurality of longitudinally extending current conductive elements spaced from each other about the periphery of the radiator and connected to provide around at least a portion of the radiator, a shunt path having an impedance to high frequency currents which is much less than that of the radiator.

2

For a better understanding of the present invention, together with other and further objects thereof, reference is had to the following description taken in connection with the accompanying drawing, and its scope will be pointed out in the appended claims.

In the drawing, Fig. 1 is a sectional view of a high frequency generator of the resonator type which includes the present invention in one form; 10 Fig. 2 is a sectional view of an alternate form of the invention; and Fig. 3 is a cross-sectional view taken along line 3—3 of Fig. 2.

Referring to Fig. 1 of the drawing, there is represented a cross-sectional view of a pulse-modulated signal generator constructed for high frequency ultra-short-wave operation and including the present invention in one form. Briefly, the generator comprises an oscillatory circuit provided by an electron-discharge device or vacuum tube 10 of the triode type and a pair of associated resonant cavities 11 and 12. Vacuum tube 10 has a tubular cathode 13, a ring-type anode 16 having a disc or skirt portion 24, and a control electrode or grid 15. The grid is in the form of a cage interposed between the cathode and the anode. At one end of a grid supporting conductor 18 there is a radiator 17, constructed in accordance with the invention and described more fully hereinafter. A contact spring 19 connects the grid with a grid conductor 20 which is coupled to a terminal 40 through an insulator bushing 21. Glass envelopes 22 and 23 make up the remainder of the tube elements. The tube also has a cathode connector and a heater prong which are received, respectively, by spring connectors 25 and 26 of an associated cathode lead-in structure 27 for supplying excitation potentials and heating current to the cathode. The cathode modulating potential is applied from a terminal 41 while the heater current is supplied through a transformer 42.

The pair of resonant cavities 11, 12 associated with the tube 10 complete the oscillatory circuit. The first cavity 11 has a hollow cylindrical outer conductor 28 and a hollow cylindrical inner conductor 30. Near the inside end of inner conductor 30 an insulator sleeve 33 is positioned with a conductor 29 in contact with the inside surface of the sleeve, the arrangement forming a blocking condenser for the grid. The corresponding end of conductor 28 is closed by a disc 36, centrally apertured to receive tube 10 and shaped to engage anode ring 24. Disc 36 orients tube 10 and electrically connects its anode structure to conductor 28.

The second resonant cavity 12 also has a hollow cylindrical inner conductor 32 and a hollow cylindrical outer conductor 31. The ends of these conductors which are remote from the triode tube 60 are closed as indicated, and insulating spacers 43

maintain the conductors in coaxial alignment. A resilient contact device 44 for engaging anode ring 24 of the tube is secured to outer conductor 31.

The described resonant cavities 11 and 12 are 5 separable to permit inserting the tube into operative relation with reference thereto. A mechanical locking arrangement, designated 45, couples the resonant cavities into one assemblage after the tube has been inserted.

The generator of Fig. 1 is similar to the well-known Colpitts oscillator. It is operated with the anode electrode of the triode vacuum tube maintained at ground potential as indicated by the connection 46. The first resonant cavity 11 15 is coupled between the anode and control electrode of the tube. It is the wave-length determining portion of the oscillator. The second resonant cavity is conductively coupled to the anode and capacitively coupled to the cathode. 20 It represents a capacitive reactance at the frequencies generated. The oscillator is normally maintained in a nonoscillatory condition but is excited for pulse modulation by modulating potentials of negative polarity and pulse wave form 25 applied to terminals 40 and 41. Each pulse of applied potential initiates oscillations in the generator which rapidly build up to saturation value and endure for the duration of the modulating pulse, thereby to generate one pulse of a pulse-modulated carrier-wave signal. In this fashion, the oscillator responds to a modulating potential of pulse wave form and produces a modulated carrier-wave signal having an envelope similar to the wave form of the modulating potential. The generated signal may be derived from a pick-up device, projecting into cavity 11 through a port 31.

Referring now more particularly to the grid structure 16-17, embodying the present invention, it is a conductive arrangement adapted to convey heat and high frequency currents from the control electrode 15 of the electron-discharge device 10 and comprises the conductor 16 of heat and high frequency currents and the thermal radiator 17 which includes a plurality of heat-conductive elements 34. These elements as shown in Fig. 1 are flat discs, coaxially aligned and secured in transverse relation to conductor 16 by brazing or other fastening means. The elements 34 are spaced along the longitudinal axis of the conductor at equal intervals to provide a large heat-dissipating area which is suitable for cooling purposes by an air blast or convection currents of other cooling gases.

The thermal radiator 17, as so far described, presents a high impedance to high frequency currents because skin effects at the operating frequency of the oscillator cause the current to flow along the outer surface or skin of each element 34 and, hence, produce a long path of high resistance.

A shunt path for the high frequency currents is provided around a major portion of the radiator by current conductive elements 35 which preferably extend in a longitudinal direction parallel to the conductor 16 and are preferably equally spaced from each other about the periphery of the radiator. As shown in Figs. 1 and 2, the outermost radiator elements 34' and 34'' may be made larger than the intervening elements 34. Strips or wires 35 of current conducting material are then secured by brazing or soldering to the two outside elements 34' and 34''. At least four such shunt paths are pro-

vided, six are preferable, and they are proportioned so that the spacing between adjacent ones of these current conductive elements is appreciably greater than any transverse dimension of such a current conductive element to provide adequate openings through which a cooling gas may flow.

The shunt path for high frequency currents provided by elements 35 has considerably less 10 impedance than the path through the radiator 17 because the current conductive elements are placed in a path that is direct, short, and on the outside of the heat radiator.

In considering the operation of the conductor shown in Fig. 1, let it be assumed that proper pulse-modulated voltages have been applied to the oscillator system and it is in working order. The major portion of the heat produced in the tube 10, as a result of the generated oscillations, is concentrated at the anode electrode. For that reason the heavy metallic disc 24 is soldered to the anode and is clamped to a heavy conductive supporting member 36. The anode electrode is grounded through the outer cylinders 28, 31 of the two resonant cavities 11, 12 and because of this direct path, adequate cooling of the anode is assured.

The control electrode or grid is more difficult to cool because connection is preferably made to it through the center of one of the resonant cavities and because it is at a high negative potential. As a means for providing an efficient heat-dissipating structure, the control electrode is secured to a heavy conductor 16 by welding or brazing. The heat generated at the grid of the vacuum tube 10 flows along the conductor 16 to the radiator 17 for dissipation by way of the heat-conductive elements 34. The current conductive elements 35 also help to dissipate heat.

To dissipate heat quickly, an air blast is preferably provided. This may be supplied by a blower (not shown) forcing air through an input port (not shown) to the radiator and out an exit port 37. In accordance with well-known design principles, the heat-conductive elements are thin in comparison to their diameter which, in turn, is large in comparison to the diameter of the heat conductor 16 on which the elements are mounted.

The path of high frequency current from the control electrode 15 to the cavity resonator 11 is along the surface of conductor 16 until the first or lowest heat-conductive element 34' is reached. Then the current travels along the bottom surface or skin of the lowest element 34' to the peripheral edge thereof. From that point the current is shunted around the four intermediate elements of the radiator by current conductive elements 35 to the topmost element 34'' where it is collected by the spring connector 18. From the connector 18 the current may flow through the condenser 33 to the resonant cavity wall 30.

If the current conductive elements 35 are not provided to furnish the shunt path as explained above, the high frequency currents flow over the surface of each of the heat conductive elements 34 in a long path of high resistance.

The form of the invention shown in Figs. 2 and 3 is the same as that shown in Fig. 1 except that the conductor 16 is continued through the radiator 17 to make a structure which is mechanically rigid. Such a form is used where the detachable spring connector 18 is not necessary. In order to facilitate the flow of high frequency currents from conductor 16 to the shunt-con-

ductive elements 35, a cone-shaped conductor 18 may be employed. It has been found that such a device reduces the impedance of the arrangement. A similar conductor may be used at each end of the radiator.

The operation of the conductor shown in Figs. 2 and 3 is generally the same as that shown in Fig. 1 except that the high frequency currents flow over the upper surface of heat-conductive element 34" to conductor 18 instead of being collected by a spring connector, such as 18.

Although the above-described embodiments disclose the invention as applied to an electron-discharge device, it is to be understood that application may also be made to any source of heat and high frequency currents.

While there have been described what are at present considered to be the preferred embodiments of this invention, it will be obvious to those skilled in the art that various changes and modifications may be made therein without departing from the invention, and it is, therefore, aimed to cover all such changes and modifications as fall within the true spirit and scope of the invention.

What is claimed is:

1. An arrangement adapted to convey heat and high frequency currents from a source comprising, a conductor of heat and high frequency currents, a thermal radiator including a plurality of heat-conductive elements of relatively large areas secured in transverse relation to and spaced along the longitudinal axis of said conductor to provide a large heat-dissipating area but presenting a high impedance to the flow of high frequency currents along said radiator, and a plurality of longitudinally extending current conductive elements spaced from each other about the periphery of said radiator and connected to provide around at least a portion of said radiator a shunt path having an impedance to high frequency currents much less than that of said radiator.

2. An arrangement adapted to convey heat and high frequency currents from a source comprising, a conductor of heat and high frequency currents, a thermal radiator including a plurality of heat-conductive elements of relatively large areas secured in transverse relation to and coaxially aligned with but spaced along the longitudinal axis of said conductor to provide a large heat-dissipating area but presenting a high impedance to the flow of high frequency currents along said radiator, and a plurality of longitudinally extending current conductive elements spaced from each other about the periphery of said radiator and connected to provide around at least a portion of said radiator a shunt path having an impedance to high frequency currents much less than that of said radiator.

3. An arrangement adapted to convey heat and high frequency currents from a source comprising, a conductor of heat and high frequency currents, a thermal radiator including a plurality of heat-conductive elements of relatively large areas secured in transverse relation to and spaced along the longitudinal axis of said conductor to provide a large heat-dissipating area but presenting a high impedance to the flow of high frequency currents along said radiator, and a plurality of longitudinally extending current conductive elements spaced from each other about the periphery of said radiator and connected between the two outside heat-conductive elements thereof to provide around a major portion of said radiator

a shunt path having an impedance to high frequency currents much less than that of said radiator.

4. An arrangement adapted to convey heat and high frequency currents from a source comprising, a conductor of heat and high frequency currents, a thermal radiator including a plurality of heat-conductive elements each having an exposed area large in comparison to the cross-sectional area of said conductor, said conductive elements being secured in transverse relation to and spaced along the longitudinal axis of said conductor to provide a large heat-dissipating area but presenting a high impedance to the flow of high frequency currents along said radiator, and a plurality of longitudinally extending current conductive elements spaced from each other about the periphery of said radiator and connected to provide around at least a portion of said radiator a shunt path having an impedance to high frequency currents much less than that of said radiator.

5. An arrangement adapted to convey heat and high frequency currents from a source comprising, a conductor of heat and high frequency currents, a thermal radiator including a plurality of heat-conductive elements of relatively large areas secured in transverse relation to and spaced along the longitudinal axis of said conductor to provide a large heat-dissipating area but presenting a high impedance to the flow of high frequency currents along said radiator, and a plurality of longitudinally extending current conductive elements so spaced from each other about the periphery of said radiator that the space between adjacent ones of said current conductive elements is greater than any transverse dimension of a current conductive element and connected to provide around at least a portion of said radiator a shunt path having an impedance to high frequency currents much less than that of said radiator.

6. An arrangement adapted to convey heat and high frequency currents from a source comprising, a conductor of heat and high frequency currents, a thermal radiator including a plurality of heat-conductive elements each having a large surface area and a thickness which is small in comparison to the diameter of said conductor, said conductive elements being secured in transverse relation to and spaced along the longitudinal axis of said conductor to provide a large heat-dissipating area but presenting a high impedance to the flow of high frequency currents along said radiator, and a plurality of longitudinally extending current conductive elements spaced from each other about the periphery of said radiator and connected to provide around at least a portion of said radiator a shunt path having an impedance to high frequency currents much less than that of said radiator.
